UNITED STATES PATENT OFFICE

FREDERIC A. DAVIDSON, OF BAYSIDE, NEW YORK, ASSIGNOR TO AMERICAN SAFETY DEVICE CO., OF NEW YORK, N. Y., A CORPORATION OF NEW YORK

CHUTE STRUCTURE

Application filed February 2, 1931. Serial No. 512,831.

This invention relates to chute structures, and more particularly to certain improvements in the construction of conducting chutes and the means for mounting the same in fixed relation to the wall of a building undergoing demolition or erection for the purpose of receiving dirt and building débris and conducting the same to a suitable collection hopper. A temporary chute structure of this type is disclosed in my pending application for patent Serial No. 464,172, filed June 27, 1930, and my present invention has for its general object and purpose to improve the construction of the chute sections in certain particulars whereby they may be assembled in superposed relation and rigidly connected with spaced vertically extending supports with greater ease and facility and also very compactly arranged when disassembled so that they will occupy relatively little space in transportation or storage.

It is a further object of my invention to provide individual chute sections of sheet metal construction which will be relatively light in weight, each of said sections being open at one side and provided with integrally formed means to removably receive closure panels for the open sides thereof.

More particularly, in one embodiment of the invention, the sheet metal chute sections are of substantially U-shaped form in cross section, the side walls of which are provided with longitudinally extending channels at the open side of the chute section to receive the closure panels, the walls of the chute section at their opposite ends being provided with continuous outwardly extending reinforcing flanges. It is also one of the detail features of my invention to provide means permanently carried by said flanges for detachably and rigidly securing the superposed chute sections in assembled relation.

With the above and other objects in view, the invention consists in the improved chute structure and in the form, construction and relative arrangement of its several parts as will be hereinafter more fully described, illustrated in the accompanying drawing, and subsequently incorporated in the subjoined claims.

In the drawing, wherein I have disclosed one simple and practical embodiment of my invention, and in which similar reference characters designate corresponding parts throughout the several views,—

55

Figure 1 is a fragmentary side elevation showing the manner of mounting and supporting the chute structure with respect to the wall of a building;

Fig. 2 is a front elevation on an enlarged scale;

Fig. 3 is a horizontal sectional view taken on the line 3—3 of Fig. 2, and

Fig. 4 is a fragmentary perspective view of two chute sections in separated relation to each other.

As herein shown, the chute structure may be built up of any desired number of units or sections as required, the said sections as they are successively assembled in superposed relation, being securely and rigidly fixed to the spaced vertically disposed supporting elements which have previously been arranged and secured in properly spaced relation to the face of the building wall. As herein shown, the spaced vertical supports for the chute structure each consists of a plurality of lengths of metal tubing indicated at 5, which may be of any desired length and are provided at their ends with suitable coupling means whereby said lengths of tubing may be detachably connected with each other. While these vertically extending supports might be anchored or fixed with respect to the wall of a building in various ways, as one simple and efficient means for this purpose, I preferably use the device disclosed in my co-pending application above referred to, and consisting of the short rods or tubes 6 securely fixed at one of their ends to the vertical tube sections 5 by means of the coupling devices indicated at 7 and extending at right angles to said tube sections and inwardly through the window openings of the building wall W. The inner ends of these short tubes 6 are similarly connected by the coupling devices 8 with the vertically disposed tubular members 9 arranged at the inner face of the building wall and at opposite sides of the window opening.

100

The chute structure comprises individual units or sections 10. The body of each of these chute sections may be conveniently formed from sheet metal of the requisite gauge, pressed or die stamped into general 5 trough shaped form, roughly U-shape in cross section and preferably tapering or decreasing in width from the open side of the chute section to the opposite closed side thereof, as clearly seen in Fig. 3 of the drawing.

10 Each of the lateral side walls 11 of the chute section has a continuous longitudinally extending inwardly opening channel 12 formed on its edge at the open side of the chute section.

15 To the opposite ends of the walls of the sheet metal chute section outwardly projecting continuous flanges 13 are welded or otherwise permanently secured. The ends of these 20 flanges abut closely against the walls of the channels 12, providing adequate reinforcement thereof at the end of the chute section, said ends of the flanges projecting laterally, and beyond the outer walls of the channels 12, and 25 thus obviating distorting or bending of the ends of the channels which might otherwise occur.

The channels 12 of each chute section adjacent the opposite ends thereof have suitably secured thereto the clamping or coupling devices indicated at 14 which are of 30 more or less conventional form, and enable the proper engagement thereof with the outer sides of the supporting tubes 5, as the chute 35 sections are successively assembled.

The flange 13 on one end of each chute section is provided with the openings indicated at 15, and at corresponding points, the flange on the opposite end of the chute section is provided with the upstanding studs 16. Thus, it will be understood that in assembling the chute sections in superposed relation, the studs 16 of one section are received through the openings 15 in the flange 40 of an adjacent chute section. Locking keys 17 are connected by short chains 18 permanently to one of the flanges 13 of each chute section. These keys are preferably in the form of tapered pins adapted to be driven 45 tightly into correspondingly tapered transverse openings 19 formed through the studs 16. Preferably, as a sound deadening means, I interpose between the adjacent flanges of the superposed chute sections a gasket strip 50 of paper, asbestos or other suitable material, which of course is likewise provided with suitably located openings to receive the studs 16. As the chute sections are successively assembled, the locking pins 17 are 55 finally driven through the openings 19 of the studs 16 and have bearing contact upon the upper surface of the flange 13 on the lower end of the upper chute section. Thus, the chute sections will be securely held in assembled relation and relative lateral shifting

movement of the end of one section relative to the other effectually prevented.

Preferably, I also provide each of the flanges 13 and the interposed gasket strip 20 at the opposite sides of the chute section 70 with additional openings indicated at 21 to receive the hooks of a block and fall or other hoisting means whereby the chute sections may be expeditiously handled in the erection or dismantling of the chute structure. 75

From the foregoing description, it will be seen that by means of my present improvements, the chute structure may be easily and quickly built up to any required height. 80

After the chute sections have been assembled in the manner above described, and rigidly connected with the vertical tubular supports 5 by means of the clamping or coupling devices 14, suitable closure panels indicated at 22, which may conveniently consist of boards 85 or planks of any desired length, are then inserted at their opposite longitudinal edges into the channels 12 of the chute sections. Certain of these boards are provided with openings therethrough to receive the outer 90 ends of inclined feed or inlet chutes 23 which extend outwardly and through the lower ends of the window openings in the wall W as seen in Fig. 1 of the drawing. In order 95 that the openings in the boards 22 may be properly located with relation to the window openings which may be variously spaced vertically from each other in different building walls, additional supplementary panel sections of relatively short lengths may be employed and interposed between the main longer panel sections 22. These panel sections 22 tightly close the open sides of the chute sections, preventing the escape of dust 100 therefrom or the entrance of water into the 105 interior of the chute.

When the use of the chute structure is no longer required, it will be evident that the several units or sections thereof may be readily disconnected and the tubular supporting 110 elements 5, 6 and 9 also quickly uncoupled. In view of the form of the chute sections, a large number of said sections can be easily nested one within another. Therefore, the chute sections together with the panel members 22 and the parts of the chute support can be very compactly arranged in a comparatively small space for purposes of storage or transportation. The tubular elements 5, 6 and 9 may conveniently be placed within 115 the nested chute sections while the boards or panels 22 can be placed over the open sides of said chute sections and finally the inlet chute sections 23 may be superimposed thereon. Thus the lateral dimensions of the 120 knocked-down structure will be confined within very narrow limits.

I have herein shown and described an embodiment of my present improvements, which I believe to be entirely practical and 125 130

serviceable for the purpose in view. While I have particularly referred to a preferred form of the sheet metal sections, it will of course be evident that the sections can be of various other cross sectional shapes as may be desired, also the several other detail parts of my present disclosure as herein referred to are susceptible of more or less variation in form, structure and arrangement, and it is therefore, to be understood that I 10 reserve the privilege of resorting to all such legitimate changes therein as may be fairly embodied within the spirit and scope of the invention as claimed.

I claim:

1. In combination with spaced parallel supports, chute sections for débris and the like arranged in aligned superimposed relation and each having an open side, adjustable means in removable connection with the sections for retaining the same in aligned superimposed relation with each other, and additional adjustable means on the walls of each chute section and at the open side thereof for retaining a removable closure panel upon the open side of each chute section to form a continuous closed channel for receiving the débris.

2. In combination with spaced parallel supports, chute sections for débris and the like each open at one side adapted to be arranged in aligned relation with the open sides thereof positioned between said spaced supports, means for detachably connecting the ends of the adjacent chute sections with each other, means carried by the sides of the chute sections releasably engaged with said supports to detachably secure the chute sections in fixed relation with each other, separable closure means for the open sides of the chute sections, and means for retaining the closure means in applied relation to the chute sections.

3. In combination with spaced parallel supports, chute sections for débris and the like each open at one side adapted to be arranged in aligned relation with the open sides thereof positioned between said spaced supports, means at the end of each section for detachably connecting adjacent chute sections with each other, adjustable means carried by the chute sections releasably engaged with said supports to detachably secure the chute sections in fixed relation with each other, separable closure means for the open sides of the chute sections, and integrally formed means on the walls of each chute section cooperating with the closure means to removably retain the latter in applied position, said integrally formed means of one section being in alignment with the means of the succeeding chute sections to form continuous channels for said closure means.

4. In combination with spaced parallel supports, chute sections for débris and the

like each open at one side adapted to be arranged in aligned relation with the open sides thereof positioned between said spaced supports, removable means for detachably connecting the ends of the adjacent chute sections together, adjustable means carried by the chute sections releasably engaged with said supports to detachably secure the chute sections in fixed relation with each other, inwardly opening longitudinal channels on the walls of each chute section at the open side thereof, to form a continuous channel through the joined sections, and closure panels for the open sides of the chute sections adapted to be slidably and removably engaged in said channels.

5. A chute structure comprising a plurality of chute sections for débris and the like each formed from sheet metal and open on one side, the walls of the chute section at the open side thereof being formed with longitudinally extending inwardly opening channels adapted to slidably receive closure means for the open side of the chute, adjustable longitudinally spaced clamping devices on each of said channels adapted to be releasably engaged with a fixed support for the chute structure, and means carried by the chute sections at the ends thereof for rigidly connecting said sections together in longitudinally aligned relation with each other, whereby to form continuously connected channels of the sections for the successive insertion of the closure means.

6. A chute structure comprising a plurality of sheet metal sections for débris and the like each open on one side thereof, each chute section at its opposite ends having a continuous flange projecting outwardly from the walls thereof, the flange on one end of each chute section having spaced studs extending therefrom and the flange at the other end thereof provided with correspondingly spaced openings to receive the studs on the opposed end of a longitudinally aligned chute section, means attached to one of the flanges of each chute section adapted to be cooperatively engaged with said studs to detachably retain the ends of adjacent chute sections in rigidly connected relation, and each of said chute sections at the open side thereof having means integrally formed with the chute walls to removably retain a closure in position over the open side of the chute section.

7. In combination with the wall of a building, a chute structure for débris, consisting of chute sections each having an open side and oppositely disposed longitudinally extending channels, said sections being adapted to be arranged in aligned relation, removable means connecting the meeting edges of each section for retaining said sections in alignment with each other, spaced parallel supports in connection with the building, spaced

adjustable clamping means on the sides of each section for rigidly connecting the same to said spaced parallel supports and closure means retained in said channels covering the open side of said sections forming a continuous closed chute.

8. In combination with the wall of a building, a chute structure for débris and the like consisting of tapered chute sections having an open side, longitudinally extending channels opposite each other at the open side thereof for retaining unbreakable closure means, the ends of the sections being outwardly flanged for resting against the flanged end of the next succeeding section, means for holding said sections together, parallel bars spaced on each side of said sections, adjustable means on the channeled portions of the sections for releasably engaging the bars, and means for engaging said bars with the building whereby to provide a chute disposed parallel with the building wall for the removal of debris and the like therefrom.

25 In testimony that I claim the foregoing as my invention, I have signed my name hereto.

FREDERIC A. DAVIDSON.
